UNITED STATES PATENT OFFICE.

FRANCIS HERBERT WENHAM, OF THE BEACON, GOLDSWORTH, WOKING,
COUNTY OF SURREY, ENGLAND.

GAS-LAMP.

SPECIFICATION forming part of Letters Patent No. 355,629, dated January 4, 1887.

Application filed December 3, 1886. Serial No. 220,583. (No model.) Patented in England February 3, 1885, No. 1,514, and August 11, 1886, No. 10,279; in Victoria May 4, 1885, No. 4,049; in New South Wales July 13, 1885, No. 6,757; in Russia October 28, 1885; in South Australia December 7, 1885, No. 629; in Queensland April 20, 1886, No. 72; in Spain June 10, 1886, No. 5,554, and in Denmark November 1, 1886, No. 814.

To all whom it may concern:

Be it known that I, FRANCIS HERBERT WENHAM, a subject of the Queen of Great Britain and Ireland, and residing at "The Beacon," 5 Goldsworth, Woking, in the county of Surrey, England, have invented certain new and useful Improvements in Gas Lamps, (for which I have obtained patents in the following countries: Great Britain, dated February 3, 1885, 10 No. 1,514; Victoria, dated May 4, 1885, No. 4,049; New South Wales, dated July 13, 1885, No. 6,757; South Australia, dated December 7, 1885, No. 629; Queensland, dated April 20, 1886, No. 72; Spain, dated June 10, 1886, No. 15 5,554; Denmark, dated November 1, 1886, No. 814; and have made applications in Russia on the 28th of October, 1885, and Great Britain on the 11th of August, 1886, No. 10,279,) of which the following is a specification.

20 My invention relates to the class of gas-lamps wherein the air supplied to the lamp is heated in its passage to the flame by means of an air-heating chamber placed above the burner, the flame being inclosed in a glass, and 25 the air-inlets and the chimney being so arranged that a cup or saucer shaped flame is obtained.

The objects of my present invention are principally to provide efficient lamps of simple construction, and wherein the orifices for the escape of gas are not liable to become clogged by carbonaceous matter.

Figure I of the accompanying drawings is 30 a vertical section of a lamp constructed according to my invention; and Figs. II and III show modifications of the lamp, as hereinafter described.

In Fig. I, A is an inner chamber situated in the center of the lamp - casing B, the tubes b 35 leading air from outside the lamp to the chamber A. The lower end of the inner chamber, A, into which the air for supplying the inside of the flame is received, is covered with a perforated plate or gauze, h, either flat, as in Figs. I and II, or preferably of a cup or dished form, as shown in Fig. III.

When the gas is lighted, the flame spreads outward under the perforated plate or gauze

h. When the glass E is closed below it, the draft through the heating-chamber A brings 50 a current of heated air from above, as indicated by the arrows, so as to depress the flame, the air entering the lamp by passing in beneath the curtain C, and then through the horizontal tubes b into the chamber A, and 55 thence through the gauze h, or its equivalent, to the flame. The curtain C protects the lamp from direct air-currents. Air is admitted through orifices b² in the cover b¹ of the lamp, as shown by the arrows, or at other suitable 60 parts, in sufficient quantity to produce complete combustion.

The burner G, which is supplied by the pipe F, is closed at the top, and has holes around its periphery.

The chamber A has gauze or its equivalent both at the top at i, and at the bottom at h, in Figs. I and II. There is a space between the said gauze or its equivalent and the top of the burner, which, as before mentioned, has orifices around its periphery or sides, and is closed at top, and there is also preferably an opening or increased air-passage in the central part of the lower gauze, h, or its equivalent, for the freer passage of air at this part. The 75 air for the supply of the outer side of the flame is taken through the openings b². E is the inclosing-glass, and the exit for the products of combustion is between the chamber A and the lamp-case to the chimney D above, 80 as shown. The gauze or its equivalent may be situated in any suitable position in or in connection with the air-chamber, and in place of gauze I may use perforated or divided plates or rings of metal, or equivalent means 85 of breaking up the air and dividing it into small streams for properly distributing it.

As shown in Fig. III, the gauze h is replaced by a plate, h², having a central opening or perforation.

It will be seen that in this lamp by the simple arrangements of parts, as shown, a regulated supply of heated air is obtained, and that a cup or saucer shaped flame is produced without the use of a reflecting flame-plate 95 above the flame, or a disk or button beneath

it; and, further, that as the gas is not highly heated before it escapes at the burner the gas-outlet orifices are not liable to be clogged by carbonaceous particles depositing in them.

5 In the arrangement, Fig. I, the upper part of the lamp can be lifted bodily off from the glass and burner beneath for lighting or other purpose, while the glass can be slid off from the supply-pipe and burner.

10 I claim as my invention—

1. In a gas-lamp, the combination of a flame-inclosing glass, a lamp-casing, an air-heating chamber having inlets for the admission of air, a gauze or plate having perforations over its entire surface, and a burner closed at the top, and having openings around its periphery and placed directly below said air-heating chamber, with an entirely free space be-

tween the bottom thereof and the top of the burner, substantially as described.

2. In a gas-lamp, the combination, with the air-heating chamber and the burner below the same, of the gauze or plate at the bottom of said chamber, through which the air passes to the flame, the central passage through the said gauze or plate being freer or of greater capacity than at the surrounding portions, substantially as described.

In testimony whereof I have signed my name to this specification in the presence of two subscribing witnesses.

FRANCIS HERBERT WENHAM.
